UNITED STATES PATENT OFFICE.

WILLIAM E. JAQUES, OF GRAND RAPIDS, MICHIGAN.

APPARATUS FOR MAKING CEMENTITIOUS PRODUCTS OR ARTIFICIAL STONE.

No. 829,014.

Specification of Letters Patent.

Patented Aug. 21, 1906.

Application filed February 15, 1904. Renewed July 2, 1906. Serial No. 324,492.

To all whom it may concern:

Be it known that I, WILLIAM E. JAQUES, a citizen of the United States of America, residing at Grand Rapids, in the county of Kent and State of Michigan, have invented certain new and useful Improvements in Apparatus for Making Cementitious Products or Artificial Stone; and I hereby declare the following to be a full, clear, and exact description of the invention, such as will enable others skilled in the art to which it pertains to make and use the same.

This invention relates to improvements in apparatus suitable for use in manufacturing cementitious products or artificial stone.

One object of this invention is to make a cementitious product or artificial stone whose constituent particles are closely compacted and which is uniform in strength and durability.

Another object is to form a vertically-arranged column of moist and unset cementitious material, to elevate the said column intermittently by successive additions of cementitious material to the lower end of the column, to remove sections successively from the upper end of the said column, and to facilitate the separation of the said sections from the upper end of the column.

Another object is not only to compact cementitious material added to the lower end of the column from below, but to utilize also and largely the weight of the cementitious column in compacting the material thus added to the said column.

Another object is to prevent any waste of moisture or cementitious slurry gravitating from the lower end of the cementitious column and to utilize such moisture or cementitious slurry in connection with fresh moist and unset cementitious material fed to the lower end of the said column.

With these objects in view, and to the end of realizing other advantages hereinafter appearing, this invention consists in certain features of construction and combinations of parts hereinafter described, and pointed out in the claims.

My improved apparatus is illustrated in the accompanying drawings, wherein—

Figure 1 is a side elevation, largely in section, of the said apparatus. Fig. 2 is a top plan of the lower portion of the apparatus, partly in section, on line 2 2, Fig. 1. Fig. 3 is a side elevation, largely in section, of the lower portion of the apparatus. In this

figure the plunger G is shown in its upper position and the plunger F appears in its inner position. Fig. 4 is a top plan of the upper portion of the apparatus. Fig. 5 is a vertical section on line 5 5, Fig. 1.

Referring to the said drawings, A designates a vertically-arranged hollow column, shaft, or tube wherein a moist and unset cementitious column is formed. The part A will hereinafter in this specification be referred to as a "shaft," in whose interior passage-way B cementitious material is accumulated to form a cementitious column C. The passage-way B extends from within the lower end to the upper end of the shaft A. The cementitious column C, composed of moist and unset cementitious material, is elevated and elongated within the shaft A by the addition to the lower end of the column of moist and unset cementitious material. The drawings illustrate the formation of and manner of elongating the column C, and sections or pieces are successively removed from the upper end of the said column, as will herein-after appear.

At one side of and adjacent to the lower end portion of the shaft A is a hopper D, which is supplied with the moist and unset cementitious material C', which is to be fed and added to the lower end of the cementitious column C, formed within and by the said shaft.

A desirable cementitious mass used in making cementitious products or artificial stone is a concrete or mixture having any suitable cementitious substance—such, for instance, as hydraulic cement—as an ingredient, and comprising also sand and moisture in suitable proportions. The cement or cementitious substance and water are first mixed together so as to form a cementitious slurry. Then this slurry is added to the sand in suitable proportions—as, for instance, in the proportions of one part, by weight, of the slurry to two parts of sand. Then the cementitious slurry and the sand are thoroughly mixed together.

The hopper D is provided at its lower end with a downwardly-discharging opening or outlet d, which connects with the interior chamber e of a horizontally-arranged case E, and a plunger F snugly fits within and is capable of reciprocation endwise of the chamber e and feed cementitious material received by and within the said chamber from the hopper D into the interior passage-way B

of the shaft A through a lateral charging aperture or inlet *a*, with which the said shaft is provided at the discharging end of the said chamber. The shaft A extends far enough 5 below the case E to accommodate the location and operation of a plunger G, which fits snugly within the lower end of the said shaft and is capable of reciprocation vertically.

The charging aperture or inlet *a* of the 10 shaft A extends upwardly from the bottom of the chamber *e*, and preferably the full width of the said chamber, as shown in Fig. 2. The aperture *a* establishes communication, therefore, between the passage-way B 15 and the chamber *e*, and preferably extends upwardly far enough above the chamber *e*, as at 10, (see Figs. 1 and 3,) to establish communication also between the outlet *d* of the hopper D and the said passage-way.

20 The plunger F is operated in any approved manner, and preferably has outwardly-projecting arms *f*, which (see Figs. 1 and 2) are provided with rollers *h*, arranged horizontally and in line endwise and at a right angle 25 to the path of the said plunger, which rollers engage with cam-forming grooves *k*, formed in a cam-wheel K, which is operatively mounted on a suitably-supported shaft L, arranged horizontally and at a right angle to the path of the 30 said plunger.

The plunger G is operated in any approved manner, and preferably has a depending stem *g*, which is provided at its lower and free end with a roller *l*, arranged horizontally 35 and at a right angle to the path of the said plunger G. The roller *l* engages the cam-forming peripheral surface of a cam-wheel M, which is operatively mounted on a suitably-supported horizontal shaft N, arranged 40 parallel with the shaft L and operatively provided with a driving-wheel *n*. The plunger G obviously lowers by gravity and is elevated by the cam-wheel M.

An operative connection between the two 45 shafts L and N is established and comprises, preferably, an endless chain O, leading over and operatively engaging sprocket-wheels I and J, which are operatively mounted on the shafts L and N, respectively.

50 The arrangement of the parts and the trend of the cam-forming surfaces of the cam-wheels K and M are such that the plunger G in its lower position, as shown in Fig. 1, has its upper and pressure-exerting face flush 55 with the bottom of the chamber *e*; that during the first position of the dwell of the said plunger in its lower position the plunger F is in its outer position; that moist and unset cementitious material is fed from the hopper 60 D into the chamber *e* in advance of the plunger F; that the plunger F is actuated forwardly or inwardly to feed the material fed in advance of the said plunger through the aperture or inlet *a* into the passage-way B 65 and onto the plunger G; that the plunger G

remains in its lower position during the inward-travel or feeding operation of the plunger F and adds the said material to the lower end of the cementitious column during the next-succeeding upward movement of the plunger G; that the plunger F does not move as far as the aperture *a* during its feeding operations, so as to avoid interruption in the communication between the chamber *e* and the inlet of the hopper D and so that any excess of material in advance of the plunger G can escape or return during the feeding operation of the said plunger G back into the said chamber or into the hopper; that the two plungers F and G make their return or idle strokes preparatory to the next-succeeding feeding operation of the plunger F, and that the plunger G in its upper position, as shown in Fig. 3, does not cover the upper end of the aperture or inlet *a* where the said inlet communicates directly with the outlet of the hopper, so that communication between the passage-way B and the interior chamber of the hopper is never interrupted and cementitious slurry or moisture gravitating from the cementitious column C or displaced from the said passage-way during the feeding operations of the plunger G can escape into the hopper and into the chamber *e*, and the cementitious slurry or moisture thus displaced or escaping from the shaft A is not only not wasted, but actually used to great advantage in insuring the presence of the required amount of cementitious substance and moisture in the charges of material successively added to the lower end of the cementitious column.

The shaft A tapers slightly downwardly from the horizontal plane at which sections are successively removed from the cementitious column formed in the said shaft to the path of the plunger G—that is, the passage-way B is gradually enlarged upwardly from the path of the plunger G to the horizontal plane where sections are removed from the upper end of the cementitious column C, so as not only to facilitate the elevation of the said column by the said plunger during the addition of fresh cementitious material to the lower end of the said column, but to seat the said column as the particles thereof become closely compacted upon oppositely-arranged slightly upwardly diverging walls of the said passage-way, and thereby adequately support the column within and from the shaft A and positively prevent any descent of the said column within the said shaft.

Very desirable results have been obtained with shafts from four to six feet high above the path of the plunger G, and the material composing the upper end of the cementitious column is in a very satisfactory condition for the severing of sections from the said end of the said column.

It will be observed that by the formation and upward feeding of a cementitious column within the shaft A the particles composing the said column are closely compacted, and the compacting of the particles of any cementitious material added to the lower end of the column is brought about not only by the plunger G in adding fresh cementitious material under pressure to the lower end of the column, but also and largely by the weight of the column.

The lower portion of the shaft A from the upper extremity of the path of the plunger G downwardly is preferably uniform in cross-section and forms a guide for the said plunger.

The cementitious column during the addition of fresh moist and unset cementitious material to the lower end of the column is lifted into an interior chamber or compartment Q' of a reciprocating frame Q, which is movable laterally in a horizontal plane at the upper end of the shaft A. The frame Q is provided with two corresponding chambers or compartments Q', which are arranged a suitable distance apart longitudinally of the path of the said frame. Each chamber Q' preferably has the dimensions required to hold a cementitious block or section capable of being subdivided into a predetermined number of bricks on edge, and the passage-way B next below the path of the frame Q corresponds in dimensions horizontally with the dimensions transversely of the said chamber. The shaft A, next below the path of the frame Q, is provided (see Figs. 1 and 5) with an upwardly-facing surface b, which extends around the passage-way B and forms a bottom bearing or seat for the frame Q, which is guided during its reciprocation by two guide-forming walls 12, with which the shaft A is provided at opposite sides, respectively, of the path of the said frame. The chambers Q' extend vertically through the frame Q, and the arrangement of the parts is such that one or the other of the chambers Q' of the said frame is exactly in line vertically and in full registry with the passage-way B, according as the said frame is in the one or the other of its positions.

Two pallets P and p are arranged a suitable distance apart longitudinally of the path of the frame Q at opposite sides, respectively, of and in close proximity to the shaft A. Each pallet rests removably upon a vertically-movable table R, which is large enough in dimensions horizontally to render it capable of adequately supporting the said pallet, and the shaft A is provided with vertically-arranged guides 13 for the said table. Each table R is provided at its under side with a roller r, which engages the cam-forming peripheral surface of a cam-wheel t, operatively mounted on a horizontally-arranged shaft T, which is suitably supported from the shaft

A. Each shaft T is arranged, therefore, a suitable distance below and at a right angle to the path of the frame Q. The shafts T of the mechanism instrumental in the operation of both tables R are operatively connected with each other by an endless chain u, leading over sprocket-wheels W and w, mounted on the different shafts T, respectively.

In Fig. 1 the frame Q is shown in position with one of its chambers Q' in full registry with the passage-way B and empty, ready to receive the upper end of the cementitious column C during the elevation of the said column during the next succeeding upward stroke of the plunger G, and the other chamber Q' of the said frame is shown occupied in the said figure by a cementitious block or section C², severed and removed from the said column and in position to descend from the engaging chamber of the said frame with the pallet P, and in the said figure the other pallet p is shown laden and in its lower position next preparatory to the replacing of the last-mentioned laden pallet by an unladen pallet.

The frame Q is provided at one end (see Figs. 1 and 4) with two outwardly-projecting arms 15, which extend longitudinally of the path of the said frame at opposite sides, respectively, of the said path and are provided with two parallel rollers 16, which extend transversely of the said frame and are arranged a suitable distance apart longitudinally of the frame. A cam-wheel 17, which has a cam-forming peripheral surface arranged to operate between the rollers 16, is operatively mounted on a shaft 18, which is arranged horizontally and transversely of and below the path of the frame Q and supported in any approved manner from the shaft A. The shaft 18 is operatively provided with a driving-wheel 20, to which power is applied in any approved manner. An endless chain 24 leads over a sprocket-wheel 23, operatively mounted on one of the shafts T, and also operatively engages a sprocket-wheel 25, operatively mounted on the shaft 18. It will be observed also that the arms 15 of the frame Q (see Figs. 1 and 4) are slotted, as at 19, to accommodate the location of the shaft 18.

The parts are so arranged and timed that each chamber Q' of the frame Q during the reciprocation of the said frame comes into full registry with the passage-way B when the other chamber Q' of the said frame is in position over a pallet; that one of the chambers Q' is brought into position over the pallet P, or the other chamber Q' is brought into position over the pallet p, according as the frame Q is in the one or the other of its positions; that the upper portion of the cementitious column C when lifted into either chamber Q' of the frame Q, so as to fill the said chamber, is severed horizontally from the remainder of the column during the next stroke of the said frame; that the different

chambers Q' are filled alternately; that sections are removed successively from the upper end of the said column, but in opposite directions alternately; that the frame Q delivers or feeds cementitious sections alternately onto the pallet of the different tables, respectively, and that each pallet-bearing table when the pallet thereon is to receive the next cementitious section moves into its upper position ready to receive the said cementitious section, which may, if desired, be subdivided into bricks or predetermined products.

Each chamber of the frame Q is quadrangular in plan and is shown large enough in dimensions horizontally and deep enough vertically to hold a cementitious block or section C², divisible into ten ordinary bricks. The said chamber is therefore four inches deep vertically, about twenty inches long, and eight inches wide and arranged with its length widthwise of the path of the frame Q, and of course the passage-way B of the shaft A next below the said path measures, therefore, about twenty inches transversely of the said path and eight inches longitudinally of the said path. Each chamber Q' when in position, registering fully and exactly with the passage-way B, as shown in Fig. 1, forms an upward extension of the said passage-way and permits the cementitious column C, formed in and by the shaft A, to be lifted into, and thereby fill, the said chamber. The parts are so arranged and timed, furthermore, that fresh, moist, and unset cementitious material is added to the lower end of the column C by the plunger G, and the said column is lifted by and during the addition of the said material to the column into a chamber Q', when the said chamber is brought into full registry with the passage-way B and against the under side of a head 14, with which the shaft A is provided, which head extends transversely of and over or bridges the path of the frame Q and extends between and is rigid with the walls or guides 12. The head 14 (see Figs. 4 and 5) is large enough in dimensions horizontally to render it capable of completely covering a chamber Q' when the said chamber is brought into full registry with the passage-way B and forms an abutment for the upper end of the elevated cementitious column and operates to trowel the top of the cementitious sections severed and removed successively by the frame Q from the said column during the reciprocation of the said frame.

The pallets P and p are large enough in dimensions to respectively receive a cementitious section C², severed from the column C and to completely cover the said section from below. A pallet suitable for receiving a cementitious section C² twenty inches long and eight inches wide would therefore be at least twenty inches long and eight inches wide and

arranged transversely of and next below the path of the frame Q. Each cementitious section C² conveyed by the frame Q onto a pallet will upon being received by the said pallet descend by gravity with the pallet during the next descent of the table bearing the said pallet; but, if desired or required, pressure by a plunger (not shown) or otherwise may be exerted on top of the said cementitious section to assist gravity in loosening the said section relative to the frame Q.

As shown in Fig. 1, the upper portion of the shaft A is preferably provided with pins x, which engage grooves y, formed in and arranged vertically of the exterior of the tables R, and the arrangement of the parts is such that the grooves y are engaged by the pins x in any position of the said tables, and the mutually-engaging pins x and grooves y are obviously instrumental in guiding the tables during the vertical reciprocation of the said tables.

I would here remark that the cementitious slurry employed with sand in the proportion hereinbefore specified in making the desired cementitious mass contains more liquid or moisture and cement or cementitious substance than necessary for incasing all of the particles of the sand of the original mass; that the solid particles of the cementitious column C are more closely compacted as the said column ascends within the shaft A; that obviously any quantity of cementitious slurry remaining free in the mass and not already employed in permanently incasing particles of sand with cement will during the ascent of the column be spread or distributed and coat any surfaces newly formed upon particles of sand during the compacting of the solid particles of the mass within the shaft A, and any cementitious moisture not finding employment in coating surfaces of sand particles will be squeezed downwardly and descend by gravity and escape at the lower end of the cementitious column, where the said moisture or thin cementitious slurry is added to fresh moist and unset cementitious material next added to the lower end of the said column. I would remark also that the upper portion of the cementitious column is equally moist transversely; that the cementitious material added to the lower end of the column becomes drier as it ascends and becomes uniform in every respect transversely of the column; that the said material upon reaching the upper end of the column is while still unset, but not too moist, in the most desirable condition for conversion into bricks or other desired cementitious products; that the said upper portion of the column is readily broken or severed from the remainder of the column; that the sections successively severed and removed from the upper end of the column are readily capable of subdivision while the material composing them has still to set

and harden, and that the pallets laden with the cementitious blocks, bricks, or products are conveyed to and left in any convenient place until the bricks or products thereon have completely set and hardened. It will be observed also that the mutually-engaging pins *x* and grooves *y* effectually prevent tipping of the tables *R* between the guides 13 and that the extension of the shaft 18 through the slots 19 in the arms 15 of the frame *Q* desirably steadies the said arms.

The process carried out in the operation of the hereinbefore-described apparatus constitutes the subject-matter of a contemporaneous application filed simultaneously with this application.

What I claim is—

1. Apparatus for making cementitious products or artificial stone, comprising a vertically-arranged material-accumulating shaft having an interior passage-way which extends from within the lower end to the upper end of the shaft; a horizontally-arranged case having an interior chamber discharging into the lower portion of the said passage-way at one side of the passage-way; a hopper discharging into the said chamber and continually communicating, at its outlet, with the aforesaid passage-way; means for feeding cementitious material from within the said chamber into the said passage-way; means for feeding the material fed into the said passage-way upwardly within the said passage-way, and means for removing sections successively from the upper end of the cementitious column formed in and by the aforesaid shaft.

2. Apparatus for making cementitious products or artificial stone, comprising an upright material-accumulating shaft having an interior passage-way which extends from within the lower end to the upper end of the shaft; a case having an interior chamber discharging into the lower portion of the said passage-way at one side of the passage-way; a hopper discharging into the said chamber and continually communicating, at its outlet, with the said passage-way; means for feeding cementitious material from within the said chamber into the said passage-way; means for feeding the material fed into the said passage-way upwardly within the passage-way, and means for removing sections successively from the upper end of the cementitious column formed in and by the aforesaid shaft.

3. Apparatus for making cementitious products or artificial stone, comprising an upright material-accumulating shaft having an interior passage-way which extends from within the lower end to the upper end of the shaft; a case having an interior chamber discharging into the lower portion of the said passage-way; means for supplying cementitious material to the said chamber adjacent

the aforesaid passage-way; means for feeding cementitious material from within the said chamber into the said passage-way; means for feeding the material fed into the said passage-way upwardly within the passage-way, and means for removing sections from the upper end of the cementitious column formed in and by the aforesaid shaft.

4. Apparatus for making cementitious products or artificial stone, comprising an upright material-accumulating shaft having an interior passage-way which extends from within the lower end to the upper end of the shaft; a case having an interior chamber discharging into the lower portion of the said passage-way at one side of the passage-way; a plunger arranged to feed cementitious material from within the said chamber into the said passage-way; means for operating the plunger; means for supplying cementitious material to the said chamber in advance of the plunger; means for feeding the said material within the said passage-way, and means for severing and removing sections successively from the upper end of the cementitious column formed in and by the aforesaid shaft.

5. Apparatus for making cementitious products or artificial stone, comprising an upright material-accumulating shaft having an interior passage-way which extends from within the lower end to the upper end of the shaft; a case having an interior chamber which discharges into the lower portion of the said passage-way at one side of the passage-way and has an inlet for receiving cementitious material; means for feeding the said material from within the said chamber into the passage-way; a plunger arranged to feed the said material upwardly within the said passage-way; means for operating the plunger, and means for severing and removing sections successively from the upper end of the cementitious column formed in and by the aforesaid shaft.

6. Apparatus for making cementitious products or artificial stone, comprising an upright material-accumulating shaft having an interior passage-way which extends from within the lower end to the upper end of the shaft; a case having an interior chamber discharging into the lower portion of the said passage-way at one side of the passage-way; a plunger arranged to feed cementitious material from within the said chamber into the said passage-way; means for operating the said plunger; means for supplying cementitious material to the said chamber in advance of the plunger; a plunger arranged to feed the said material upwardly within the said passage-way; means for operating the last-mentioned plunger, and means for severing and removing sections successively from the upper end of the cementitious column formed in and by the aforesaid shaft, and the parts being so arranged and timed

that the addition of material to the lower end of the said column and the removal of a section from the upper end of the column occur alternately.

- 5 7. Apparatus for making cementitious products or artificial stone, comprising an upright material-accumulating shaft having an interior passage-way which extends from within the lower end to the upper end of the 10 shaft; a case having an interior chamber discharging into the lower portion of the said passage-way at one side of the passage-way; means for feeding cementitious material from within the said chamber into the said passage-way; means for feeding the material upwardly within the passage-way, and means for severing and removing sections successively from the upper end of the cementitious column formed in and by the aforesaid shaft, 15 and the parts being so relatively arranged that the addition of material to the lower end of the said column and removal of a section from the upper end of the column occur alternately.
- 20 8. Apparatus for making cementitious products or artificial stone, comprising an upright material-accumulating shaft having an interior passage-way which extends from within the lower end to the upper end of the 25 shaft; a case having an interior chamber discharging into the lower portion of the said passage-way at one side of the passage-way; means for feeding cementitious material from within the said chamber into the said passage-way; means for feeding the material fed into the said passage-way upwardly within the passage-way, and means for removing sections successively from the upper end of the 30 cementitious column formed in and by the aforesaid shaft.

- 35 9. Apparatus for making cementitious products or artificial stone, comprising an upright material-accumulating shaft having an interior passage-way which extends from within the lower end to the upper end of the 40 shaft; means for supplying cementitious material to the lower portion of the said passage-way; means for feeding the material fed into the said passage-way upwardly within the 45 passage-way, and means for removing sections from the upper end of the cementitious column formed in and by the aforesaid shaft.

- 50 10. Apparatus for making cementitious products or artificial stone, comprising an upright material-accumulating shaft having an interior passage-way which extends from within the lower end to the upper end of the 55 shaft; a case having an interior chamber which discharges into the lower portion of the said passage-way at one side of the passage-way and has an inlet for receiving cementitious material; means for feeding the said material from within the said chamber into the passage-way; means arranged to 60 feed the said material upwardly within the

said passage-way, and means for removing sections successively from the upper end of the cementitious column formed in and by the aforesaid shaft.

- 65 11. Apparatus for making cementitious products or artificial stone, comprising an upright material-accumulating shaft having an interior passage-way which extends from within the lower end to the upper end of the shaft; means for supplying cementitious material to the lower portion of the said passage-way; means for feeding the material upwardly within the passage-way, and means for removing sections successively from the upper end of the cementitious column formed in and by the aforesaid shaft, and the parts being so relatively arranged that the addition of material to the lower end of the said column and removal of a section from the upper end of the column occur alternately.

- 70 12. Apparatus for making cementitious products or artificial stone, comprising a frame arranged to reciprocate in a horizontal plane and having a chamber extending vertically therethrough; means for actuating the 75 said frame; an upright material-accumulating shaft extending from the path of the said frame a suitable distance downwardly and having an interior passage-way which extends from within the lower portion of the 80 shaft to the said path; a bottom bearing or seat for the said frame at the upper end of the shaft and extending around the aforesaid passage-way; guides formed on the said shaft for the aforesaid frame; a vertically-movable 85 table arranged at one side of the shaft and having a range of movement next below the said path; means for actuating the table; a removable pallet seated upon the table, and means for upwardly actuating a cementitious 90 column formed in the aforesaid passage-way, and the arrangement of the parts being such that the aforesaid chamber in the aforesaid frame shall be in full registry with the said 95 passage-way or over the aforesaid pallet according as the said frame is in the one or the other of its positions.

- 100 13. Apparatus for making cementitious products or artificial stone, comprising a frame capable of movement in a horizontal 105 plane and having a chamber extending vertically therethrough; an upright material-accumulating shaft extending from the path of the said frame a suitable distance downwardly and having an interior passage-way 110 which extends from within the lower portion of the shaft to the said path; a bottom bearing or seat for the said frame at the upper end of the 115 and formed upon the shaft; guides for the frame; a table movable up and down at one 120 side of the shaft next below the said path; means for actuating the table, and a removable pallet seated upon the table, and the arrangement of the parts being such that the aforesaid chamber shall be in full registry 125 130

with the aforesaid passage-way or over the pallet according as the aforesaid frame is in the one or the other of its positions.

14. Apparatus for making cementitious products or artificial stone, comprising a frame capable of movement in a horizontal plane and having a chamber extending vertically therethrough; an upright material-accumulating shaft extending from the path of the said frame a suitable distance downwardly and having an interior passage-way which extends from within the lower portion of the shaft to the said path; means for guiding the said frame; a head rigid with the shaft and arranged next above the aforesaid path and large enough in dimensions horizontally to render it capable of covering the aforesaid chamber when the aforesaid frame is in position with the said chamber in full registry with the aforesaid passage-way, and a pallet removably seated at one side of the shaft below the said path, and the arrangement of the parts being such that the aforesaid chamber shall be in full registry with the aforesaid passage-way or over the pallet according as the aforesaid frame is in the one or the other of its positions.

15. Apparatus for making cementitious products or artificial stone, comprising a frame arranged and capable of reciprocation in a horizontal plane and having two chambers extending vertically therethrough and arranged a suitable distance apart longitudinally of the path of the frame; an upright material-accumulating shaft extending from the said path downwardly and having an interior passage-way which extends from within the lower end of the shaft to the said path; means for guiding the said frame; a stationary head arranged next above the aforesaid path and large enough in dimensions horizontally to render it capable of covering one of the aforesaid chambers; two removably-seated pallets arranged a suitable distance apart longitudinally of the aforesaid path at opposite sides respectively of the shaft, and the arrangement of the parts being such that one of the aforesaid chambers shall be brought over one of the pallets or the other of the said chambers shall be brought over the other pallet according as the aforesaid frame is in the one or the other of its positions, that when either chamber is over a pallet the other chamber is in registry with the aforesaid passage-way, and that either chamber, when in full registry with the said passage-way, is covered by the aforesaid head.

In testimony whereof I sign the foregoing specification in the presence of two witnesses.

WILLIAM E. JAQUES.

Witnesses:

C. H. DORER,
VICTOR C. LYNCH.

respectively, and the arrangement of the parts being such that one of the aforesaid chambers shall be brought over one of the pallets or the other of the said chambers shall be brought over the other pallet according as the aforesaid frame is in the one or the other of its positions, that when either chamber is over a pallet the other chamber is in registry with the aforesaid passage-way, and that either chamber, when in full registry with the said passage-way, is covered by the aforesaid head.

16. Apparatus for making cementitious products or artificial stone, comprising a frame arranged and capable of reciprocation in a horizontal plane and having two chambers extending vertically therethrough and arranged a suitable distance apart longitudinally of the path of the frame; an upright material-accumulating shaft extending from the said path downwardly and having an interior passage-way which extends from within the lower end of the shaft to the said path; means for guiding the said frame; a stationary head arranged next above the aforesaid path and large enough in dimensions horizontally to render it capable of covering one of the aforesaid chambers; two removably-seated pallets arranged a suitable distance apart longitudinally of the aforesaid path at opposite sides respectively of the shaft, and the arrangement of the parts being such that one of the aforesaid chambers shall be brought over one of the pallets or the other of the said chambers shall be brought over the other pallet according as the aforesaid frame is in the one or the other of its positions, that when either chamber is over a pallet the other chamber is in registry with the aforesaid passage-way, and that either chamber, when in full registry with the said passage-way, is covered by the aforesaid head.
